UNITED STATES PATENT OFFICE

135,871

DESIGN FOR A CARD HOLDER

Alvin M. Ferrier, Lowell, Mass.

Application March 4, 1943, Serial No. 109,659

Term of patent 3½ years

To all whom it may concern:

Be it known that I, Alvin M. Ferrier, a citizen of the United States of America, residing at Lowell, in the county of Middlesex and State of Massachusetts, have invented a new, original, and ornamental Design for a Card Holder, of which the following is a specification, reference being had to the accompanying drawing, forming part thereof.

Fig. 1 is a front elevational view of a card holder showing my new design.

Fig. 2 is a perspective view as from the front left and

Fig. 3 is a perspective view as from the top front thereof.

I claim:

The ornamental design for a card holder, as shown.

ALVIN M. FERRIER.
